Marie Kylar
INVENTOR
BY
Victor J. Evans
ATTORNEY

Jno. Babie Jr.
WITNESS:

UNITED STATES PATENT OFFICE.

MARIE KYLAR, OF CAMDEN, NEW JERSEY.

WASHTUB.

Application filed October 7, 1922. Serial No. 593,048.

To all whom it may concern:

Be it known that I, Mrs. MARIE KYLAR, a citizen of the United States of America, residing at Camden, in the county of Camden 5 and State of New Jersey, have invented new and useful Improvements in Washtubs, of which the following is a specification.

This invention relates to washtubs and particularly to tubs provided with washboards 10 as an integral part thereof, and one of the principal objects is to produce a device of this nature which shall be simple of construction, cheap to manufacture, and highly efficient for the purpose for which it is de- 15 signed.

Another object is to provide a receptacle 20 under the washboard wherein may be stored the clothes line, clothes pins or any other articles desired. The tub is especially de- 25 signed for use in small apartments and by people who are traveling. It is so arranged that when hung out the receptacle and washboard are completely hidden from view, and the tub presents the appearance of an ordinary device of this nature.

With the above described and other objects in view, the invention resides in certain novel construction, in combinations and arrangements of parts, the essential features of 30 which are hereinafter fully described, are particularly pointed out in the appended claims, and are illustrated in the accompanying drawing, in which:

Figure 1 is a top plan view of my im- 35 proved washtub.

Figure 2 is a vertical section taken in line 2—2 of Figure 1.

Figure 3 is a horizontal section taken substantially in line 3—3 of Figure 2.

Like characters of reference refer to like parts in the several views.

Referring to the drawing in detail, 10 represents a washtub which may be of any usual and suitable construction but is preferably of galvanized iron. A piece of metal 45 is folded so as to form upright side portions 11 and 12, and an intermediate backing-up portion 13. At the juncture of the portions

11 and 13, the metal is folded upon itself so as to form a lip 14 and groove 15; and 50 similarly at the line of juncture of the portions 12 and 13, the metal is bent to form a lip 16 and groove 17. A base 18 spans the lips 14 and 16 at their upper ends. The edges of the entire strip where they contact with the side wall and bottom of the tub are secured thereto in water-tight relation 55 by solder or other suitable means.

A pivot rod 19 is rotatably mounted in the sides 11 and 12 near the backing-up portion 13 and carries a cover 20 having a rolled-over edge 21 which is adapted to grip the edge of the tub to hold the cover 20 in closed position. A washboard 22 of any suitable and desirable construction and ma- 60 terial is removably supported in the slides 15 and 17.

While I have described what I deem to be the most desirable embodiment of my invention, I do not limit myself to the specific details of construction of material, nor to anything less than the whole of my invention as defined in the appended claims. 70

What I claim:

1. A device of the class described, comprising a metallic tub and a receptacle in said tub formed of a single piece of metal having its bottom and side edges attached in water-tight relation to the bottom and sides of the tub, and formed with slide-ways 75 80 adapted to receive the side edges of a washboard.

2. A device of the class described, comprising a metallic tub and a receptacle in said tub formed of a single piece of metal having its bottom and side edges attached in water-tight relation to the bottom and sides of the tub, and formed with slide-ways 85 90 adapted to receive the side edges of a washboard, and a cover for said receptacle mounted at one edge on said piece of metal and having its opposite edge formed to grip the edge of the tub.

In testimony whereof I affix my signature.

MARIE KYLAR.
